ATTORNEY

UNITED STATES PATENT OFFICE.

CHARLES G. WAHLSTROM, OF DALLAS, TEXAS.

TRIPLE-ACTING, FORCE, SUCTION, AND VACUUM PUMP.

Application filed January 6, 1925. Serial No. 880.

This invention relates to pumps and especially to the new and novel construction whereby the pistons are made to ascend and descend either singly or in pairs. It relates 5 also to the novel way by which the apparatus can be kept clean and free from obstructions.

The principal object of the invention is to provide a most powerful apparatus for 10 pumping where conditions require very great force or suction by employing the screw-thread principle for the raising and lowering of the pistons.

Another object of the invention is to provide a pump with a self cleaning feature, whereby an oil or other well and the working parts of the pump may be kept free 15 from congestion through extraneous matter.

20 The pump is of few parts and can be operated effectively with a single piston or with a pair of pistons or with several pistons and is of an economical manufacture.

The invention will be more fully understood by the following description and accompanying drawings which form a part 25 hereof, and in which:

Fig. 1 is a vertical sectional view of the pump, illustrating the cylinder, the pistons 30 and the piston rod in one position.

Fig. 2 is a similar view illustrating the reverse position of the pistons and piston rod and showing the two pairs of pistons drawn together.

35 Fig. 3 is a vertical sectional view illustrating the upper and the lower parts of the invention.

Fig. 4 is a vertical sectional view illustrating a cylinder and a piston in position 40 to descend and also showing a section of the piston rod.

Fig. 5 is a cross sectional view at line A—A in Fig. 4 illustrating the inner and the outer threadings of the pistons, and the 45 spiral opening at the lower end through which the fluid passes.

Referring more in detail to the drawings:

1 denotes the cylinder shaped and threaded to fit pistons 5^a and 5^b, forming stages 50 or pumping units, placed at required heights in well and connected with one another by tubings or pipes (not shown in the drawings) forming a continuous whole.

55 2 denotes the outlet of fluid.

3 denotes the piston rod shaped and threaded to the inner side of pistons 5, the piston rod is also extended by tubings in like manner with cylinders, forming a continuous channel for steam or fluid to be 60 forced down, into the bottom of pump through the perforations 4.

5 denotes the pumping-pistons with the outer side threaded to the cylinder and the inner side threaded to the piston rod, always reversing the threading so that when the outer threading 5^a is right turn the inner threading 3^a is left turn. The outer threading of the reciprocating piston 5^b is left turn and the inner threading 3^b is right turn. 70 The pistons have an open space 5^c, in Figs. 4 and 5, which runs spirally parallel with the inner threading, allowing passage for the fluid. The open chamber 5^d in Fig. 4 provides free vertical motion of pistons. 75

6 denotes a valve which opens when piston descends and closes when piston ascends. A valve may be placed either at the top 80 or at the bottom or at both places in the pistons.

7 denotes valve-guards.

8 denotes piston rings to prevent leakage.

9 denotes a sprocket-wheel fastened to the piston rod 3 and is geared to 10 which denotes a rod leading from the source of motive-power. This rod is held in place by roller 11.

12 denotes a frame carrying the pump and holding the parts in place.

13 denotes a means of connecting a steam-pipe 14 with the piston rod and providing a joint with freedom of rotary motion.

15 denotes apertures for ingress of fluid.

The operations of the invention may be 95 more fully understood by the following explanations.

When motive power is applied to rod 10, causing a right-turn rotary motion of wheel 9, and this in turn rotary motion of piston 100 rod 3, a three-fold action of piston 5^b is brought about. First, a rotating motion, somewhat slower than that of the piston rod. Second, an ascending motion by means of the inner right-turn threading. Third, this 105 rotating motion causes a further and the main lifting-action to take place by means of the outer or left-turn threading of the piston. While this ascending motion takes place with piston 5^b, a simultaneous and 110

reciprocating motion operates piston 5^a which thereby is forced downwards. When pistons 5^b, Fig. 2, have ascended and pistons 5^a have descended to the full extent as illustrated in Fig. 1, the motion of rod 10 and the piston rod 3 is reversed, and as a consequence thereof the pistons 5^a, Fig. 1, having now been charged with a new load of fluid, commence their upward journey forcing their charge up through the descending pistons 5^b next above. The pistons 5^a are also simultaneously sucking more fluid up through the descending piston 5^b next below.

The principal improvements over my Letters Patent #1,513,302, issued October 28, 1924, reside in the spiral or equivalent connections between the piston rod and the pistons, whereby said pistons are rotated in opposite directions as they reciprocate toward and from each other, thereby producing greater efficiency; together with the opposite screw-threads or spirals between the cylinders and the pistons which give a longer and more powerful stroke.

It should be understood that modifications and changes may be made in the construction to adapt the pump to the various conditions and usages coming within the meaning and spirit of the following claims:

1. A pump for oil wells and the like including a cylinder, formed with an inlet at its lower end for submersion in the well, a piston rod in the cylinder, a plurality of pairs of pistons carried by the rod, each piston having a spiral thread, means carried by the cylinder and received in the threads of the pistons for reciprocating the latter upon rotation of the piston rod, a valve controlled port in each piston, said threads of the pistons of each pair being arranged so that upon rotation of the rod said pistons will have an alternate approaching and receding movement and the adjacent pistons of the adjacent pairs of pistons will have a like alternate approaching and receding movement so as to provide continuous flow of the fluid being pumped, and means on the piston rod engaging the pistons for ro-

tating those of each pair in opposite directions.

2. A pump for oil wells and the like including a cylinder, formed with an inlet at its lower end for submersion in the well, a piston rod in the cylinder, a plurality of pairs of pistons carried by the rod, each piston having a spiral thread, means carried by the cylinder and received in the threads of the pistons for reciprocating the latter upon rotation of the piston rod, a valve controlled port in each piston, said threads of the pistons of each pair being arranged so that upon rotation of the rod said pistons will have an alternate approaching and receding movement and the adjacent pistons of the adjacent pairs of pistons will have a like alternate approaching and receding movement so as to provide continuous flow of the fluid being pumped, and spiral threads on the piston rod, the rod thread for each piston being opposite to its thread on its surface.

3. A pump for oil wells and the like including a cylinder, formed with an inlet at its lower end for submersion in the well, a piston rod in the cylinder, a plurality of pairs of valved pistons carried by the rod, spiral threads carried by the cylinder for reciprocating the pistons upon rotation of the piston rod, and spiral threads on the pistons for engaging the first threads whereby the pistons are reciprocated, and spiral threads on the piston rod engaging in each piston and opposed to cylinder threads and to each other, whereby each piston of a pair is rotated in an opposite direction.

4. A pump for wells including a cylinder formed with upper and lower internal spiral threads spaced apart, hollow pistons mounted in the cylinder and having external spiral threads engaging the cylinder threads, a piston rod extending through the pistons having spiral threads, internal spiral threads engaging the piston rod threads, the pistons having spiral fluid passages, and a valve for each piston.

CHARLES G. WAHLSTROM.
